UNITED STATES PATENT OFFICE.

CHARLES W. MANZEL, OF BUFFALO, NEW YORK, ASSIGNOR, BY MESNE ASSIGNMENTS,
TO J. L. OSGOOD, OF BUFFALO, NEW YORK.

LUBRICATOR.

1,019,167.

Specification of Letters Patent.

Patented Mar. 5, 1912.

Application filed August 13, 1906. Serial No. 330,372.

To all whom it may concern:

Be it known that I, CHARLES W. MANZEL, a citizen of the United States, residing at Buffalo, in the county of Erie and State 5 of New York, have invented a new and useful Improvement in Lubricators, of which the following is a specification.

This invention relates generally to force feed lubricators, and more particularly to 10 a lubricator of this class which is designed to supply oil to the engine-cylinders and other parts of an automobile.

One of the objects of the invention is the provision of a light, neat and compact lubricator of this character.

Further objects are to provide the force pumps with convenient means for regulating the quantity of oil delivered by the same; to provide simple and reliable means 20 for reciprocating the pump-plungers, and to improve the construction of the lubricator in other respects.

In the accompanying drawings consisting of 4 sheets: Figure 1 is a transverse vertical 25 section of the lubricator in line 1—1, Fig. 2. Fig. 2 is a vertical longitudinal section in line 2—2, Fig. 1. Fig. 3 is a transverse vertical section in line 3—3, Fig. 4. Fig. 4 is a horizontal section in line 4—4, Fig. 1.

30 Similar letters of reference indicate corresponding parts throughout the several views.

A indicates the body or reservoir of the lubricator which when used on an automobile is mounted on the dash board A¹. The body shown in the drawings is of rectangular form and preferably constructed of sheet metal. It has a removable top or cover B provided with a filling tube b which is normally closed by a cap b¹. From this filling tube a strainer b² is preferably suspended, for intercepting any solid foreign substances in the oil.

C indicates the barrels and C¹ the pistons 45 or plungers of a plurality of force pumps arranged horizontally in the lower portion of the oil reservoir and adapted to deliver oil to the engine cylinders and other parts of the automobile or other machine to be lubricated. These pumps are preferably 50 double-acting and for this purpose each pump barrel comprises a primary cylinder c and a secondary cylinder c¹ arranged in line with each other and connected by an integral web c², a single piston C¹ being ar-

ranged in the cylinders of each pump. The primary cylinder of each barrel is provided in its top with an inlet port d which is controlled by the adjacent portion of the piston and which when uncovered allows the 60 oil to flow from the reservoir into said cylinder. Beyond this inlet port, the primary cylinder is provided with a delivery port or passage d¹ containing a spring-pressed check valve d². The casing of this valve is 65 connected by a pipe e with a drip nozzle e¹ arranged in the upper portion of a sight chamber E located within the reservoir. This chamber is mounted on the front wall of the reservoir and provided in its front 70 side with a transparent pane e². The chamber E is common to and extends throughout the entire series of drip nozzles e¹. Within the sight chamber and underneath each drip nozzle is arranged a cup or funnel f which 75 receives the drops of oil from the nozzle and from which the oil is conducted to the inlet port g of the secondary pump cylinder c¹ by a pipe g¹, this inlet port being controlled by the adjacent portion of the piston C¹. 80 The secondary cylinder c¹ is provided in its lower side beyond its inlet port g with a discharge port or passage h which is formed in a hollow depending screw stem h¹ passing through an opening in the bottom of the 85 reservoir. Upon the projecting end of this stem is screwed a coupling i, the reduced lower end of which receives a delivery pipe or conduit I leading to one of the 90 parts to be lubricated, a suitable stuffing box i¹ being applied to the lower end of the coupling. The pump barrel is held from turning, in tightening said coupling by a stop-pin j projecting from the bottom of the oil reservoir into a socket or opening 95 in the lower side of the barrel, as shown in Figs. 1 and 2. A suitable check valve k is arranged in the discharge passage h of each secondary cylinder c¹ to prevent the return of the oil into the latter.

100 It will now be understood that when the piston of one of the force pumps moves toward the rear wall of the oil reservoir, its front end uncovers the inlet port d of the primary cylinder c, allowing the latter to 105 become filled with oil. When the piston moves in the opposite direction, it expels said charge of oil past the check valve d² and through the pipe e into the drip nozzle e¹, whence it descends by drops into the cup 110

- f. From this cup the oil flows through the pipe g^1 and the secondary inlet port g into the secondary cylinder c^1 from which latter it is expelled into and through the delivery pipe I on the rearward stroke of the piston. A charge of oil is thus expelled from the secondary cylinder of each pump at the same time that a charge is drawn into the primary cylinder, and vice versa.
- 10 Each pump is constructed to deliver less oil from its primary than from its secondary cylinder, in order to prevent the oil from overflowing the corresponding cup f . For this purpose, the inlet ports d, g of the two cylinders of each pump are so arranged that the inlet port of the primary cylinder is uncovered to a greater extent than the inlet port of the secondary cylinder, when the corresponding end of the piston has 15 fully retreated. It follows that upon the forward or effective stroke of the primary portion of the piston the inlet port of the primary cylinder is fully covered later than is the corresponding port of the secondary cylinder upon the effective stroke of the secondary portion of the piston and a greater quantity of the oil is therefore allowed to leak or return from the primary cylinder into the reservoir than from the 20 secondary cylinder, causing the primary cylinder to deliver less than the secondary cylinder. The dotted line x in Fig. 1 indicates the extent to which the secondary portion of the piston covers the corresponding inlet 25 port g when at the end of its return stroke.

The pistons of the several pumps may be driven from a rotary or other movable part of the automobile or other machine by any suitable means, but they are preferably reciprocated by the driving mechanism shown in the drawings, which is constructed as follows:

L is a rock-frame arranged lengthwise in the oil reservoir and having trunnions l 45 which are supported in bearings l^1 extending inwardly from the end walls of the reservoir, as shown in Fig. 2. From this rock-frame depend arms m having bifurcated lower ends which straddle pins n 50 passing transversely through the pistons C^1 , the pin of each piston projecting beyond the sides thereof and being engaged by two arms of the rock-frame, as shown in Fig. 2. The pins n play in the spaces between the primary and secondary cylinders of the pumps. The rock-frame L is provided at one end 55 with a pair of jaws o which straddle an eccentric P journaled on a horizontal stud p projecting from the adjacent wall of the reservoir. Upon the hub of this eccentric is secured a worm wheel q which meshes with a worm q^1 mounted on a driving shaft R. This shaft turns in a suitable bearing R^1 secured in the rear wall of the reservoir 60 and extending through the dash board A¹,

the projecting end of the shaft carrying a grooved pulley R^2 for driving it from a rotary shaft of the automobile, not shown. In the preferred construction illustrated in Figs. 1 and 3, the bearing R^1 is provided at its outer end with a stuffing box r . It is apparent that the eccentric P is rotated from the driving shaft through the worm gearing q, q^1 , and that the eccentric in turn imparts a rocking movement to the frame L 70 by acting upon the jaws o .

In the preferred construction shown in the drawings, the unequal delivery of the primary and secondary cylinders of the pump hereinbefore described is produced by arranging the inlet ports d and g at equal distances from a vertical line intersecting the axis of the trunnions l , while the portion of the piston C^1 extending from the center of its pin n to the end thereof working in the primary cylinder, is shorter than the portion of the piston extending from said center to its opposite end.

The primary cylinder of each pump is preferably provided with a regulating piston or follower s by which the capacity or internal area of said cylinder can be varied to feed or deliver a greater or less predetermined quantity of oil. As shown in Fig. 1, this follower is fitted in an extension s^1 of the primary cylinder which communicates with the latter and is arranged in line therewith. The outward movement of the follower is limited by an adjustable stop plate or abutment T arranged opposite its outer end and having a screw threaded opening which receives a rotary adjusting screw t . The stem of this screw passes through the front wall of the oil reservoir and terminates in a knob or button, as shown. The screw is suitably held against longitudinal movement in the wall of the reservoir and the stop-plate is held from turning on the screw by bearing at its flat lower edge upon the bottom of the reservoir, so that upon turning the screw, the stop plate is adjusted toward or from the follower s . The opposing end of the latter is hollow or recessed, as shown, to receive the end of the adjusting screw when the latter projects beyond the stop-plate T.

Upon the forward stroke of the piston C^1 in the primary cylinder c , the regulating follower s is forced outward by the column of oil in said cylinder until the follower strikes the corresponding stop-plate T, the oil entering the portion of the extension s^1 vacated by the displaced follower. As soon as the follower is thus arrested, the continued pressure in the primary cylinder overcomes the spring of the check valve d^2 , opening the latter and delivering a greater or less charge of oil through the drip nozzle c^1 into the cup f , according to the extent of travel of the follower permitted by 120 125 130

its stop. As the piston of the pump has a uniform predetermined stroke, the capacity of the primary cylinder c is augmented more or less by its extension s^1 , according as the 5 follower is allowed to recede to a greater or less extent by its stop. It follows that by increasing the capacity of the primary cylinder, a smaller quantity of oil will be pumped through the sight chamber E and 10 delivered into the secondary cylinder c^1 of the pump. Hence, if it is desired to deliver the maximum quantity of oil, the stop plate T is adjusted to its innermost position, while if a smaller quantity is to be supplied, 15 the stop-plate is moved outwardly or away from the adjacent end of the pump barrel a greater or less distance.

By arranging the regulating follower, as shown, the same is located below the level of 20 the inlet port d of the primary pump, thereby submerging the follower at all times and preventing leakage of the atmosphere past the same into the primary cylinder c . U is a gage glass preferably arranged in 25 one of the front corners of the oil reservoir, as shown in Figs. 3 and 4.

The multiple lubricator herein shown has six force-pumps and a like number of delivery pipes or feeds, but a greater or less 30 number may obviously be employed, if desired.

Aside from the advantages of a reliable sight feed and means for regulating the quantity of oil delivered by the pumps, the 35 lubricator is neat, light and compact in construction and comparatively free from projections, rendering it especially desirable for use on automobiles.

I do not wish to claim broadly in this application the adjustable follower s , as the 40 same forms the subject of Letters Patent of the United States No. 920,769, granted to me May 4, 1909.

I claim as my invention:

45 1. In a lubricator, the combination of a reservoir, a pump supplied therefrom and comprising a primary cylinder, a secondary cylinder and a piston common to both cylinders, a conduit connecting the outlet of 50 the primary cylinder with the inlet of the secondary cylinder, and a sight device arranged in said conduit, the primary portion of the pump being constructed to deliver a smaller quantity of oil than the secondary 55 portion thereof, substantially as set forth.

2. In a lubricator, the combination of a reservoir, a pump supplied therefrom and comprising a primary cylinder, a secondary cylinder and a piston common to both cylinders, the primary cylinder having an inlet port communicating with the reservoir, a

sight device connected with the discharge port of the primary cylinder, and a conduit connecting the sight device with the inlet port of the secondary cylinder, the primary 65 portion of the pump having its ports constructed and arranged to deliver a smaller quantity of oil than the secondary portion thereof, substantially as set forth.

3. In a lubricator, the combination of a reservoir, a pump supplied therefrom and comprising a primary cylinder, a secondary cylinder and a piston common to both cylinders, the primary cylinders having an inlet port communicating with the reservoir, 70 a sight device connected with the discharge port of the primary cylinder, and a conduit connecting the sight device with the inlet port of the secondary cylinder, the inlet ports of the two cylinders and the piston being so arranged that the primary part 75 of the piston uncovers the inlet port of the primary cylinder to a greater extent than the secondary part of the piston uncovers the inlet port of the secondary cylinder, 80 substantially as set forth.

4. In a lubricator, the combination of a reservoir, a pump supplied therefrom, a follower arranged in one end of the pump cylinder, a stop plate arranged opposite the 90 outer end of the follower, and an adjusting screw engaging said plate and passing through the wall of the reservoir, substantially as set forth.

5. In a lubricator, the combination of a reservoir, a pump supplied therefrom, a follower arranged in one end of the pump cylinder, a non-rotary stop plate arranged opposite the outer end of the follower, and a rotary adjusting screw held against longitudinal movement in the wall of the reservoir 100 and engaging said stop-plate, substantially as set forth.

6. In a lubricator, the combination of a reservoir, a plurality of pumps arranged in the lower portion of the reservoir and supplied therefrom, a single rock frame journaled in the reservoir and connected with the several pump-pistons, said frame being provided within the reservoir with a pair of 105 actuating jaws, a rotary eccentric engaging between said jaws, a driving shaft, and worm gearing also arranged in the reservoir and connecting the eccentric with said shaft, substantially as set forth.

Witness my hand this 9th day of August, 110 1906.

CHARLES W. MANZEL.
